UNITED STATES PATENT OFFICE.

TILLMAN B. WORTHINGTON, OF SCOTLAND, PENNSYLVANIA, ASSIGNOR OF ONE-HALF
TO ANNA MORTON BAMBRICK, OF SCOTLAND, PENNSYLVANIA.

CONVERTIBLE CHAIR AND TABLE.

1,425,354.

Specification of Letters Patent. Patented Aug. 8, 1922.

Application filed January 3, 1922. Serial No. 528,645.

To all whom it may concern:

Be it known that I, TILLMAN B. WORTHINGTON, a citizen of the United States of America, residing at Scotland, in the county of Franklin and State of Pennsylvania, have invented new and useful Improvements in Convertible Chairs and Tables, of which the following is a specification.

The object of the invention is to provide a simple and relatively inexpensive, and at the same time strong and durable folding structure adapted to be arranged to occupy a comparatively small space for transportation or storage and having means whereby it may be set up to form either a chair or a table suitable for camping and other emergency purposes; and with this object in view the invention consists in a construction and combination of parts of which a preferred embodiment is shown in the accompanying drawings, wherein:—

Figure 1 is a perspective view of the device set up for use as a chair.

Figure 2 is a similar view showing the device set up as a table.

Figure 3 is an edge view showing the device folded.

Figure 4 is a side view of the device showing it set up as a chair.

Figure 5 is a detail in perspective of the seat section showing the underside thereof.

Figures 6 and 7 are sectional views of the device in the form shown in Figure 2 respectively in the planes of the bracing loops or members.

The apparatus includes essentially a seat section 10 and a back section 11 which in the construction illustrated are shown as though constructed of single flat boards or plates but which in practice may be of any preferred framed construction having panels or fillers of cane or upholstered in any preferred manner to afford convenience to the occupant thereof particularly when the device is set up as a chair; a support or leg structure carried by the seat section and consisting of intersecting pivotally connected looped leg frames 12 and 13; connecting links 14 between the back section and one of the leg frames, and bracing loops or members 15 and 16 carried by the back section and adapted to be used in supporting the

back section in the horizontal position when the device is set up as a table.

The looped leg frames are pivotally connected at 17 and are adapted as indicated in Figure 3 to be folded into a compact flat form in a common plane, and the upper end of the frame 12 is pivotally mounted as at 18 upon the seat section adjacent to its rear edge and preferably on the side edge thereof as shown, so that when folded the seat section nests within the folded leg sections or frames, as also shown in Figure 3.

The seat section is provided at its front edge with rests 19 consisting of hooks for engagement with a cross rod 20 connecting the upper ends of the side members of the leg frame 13, and as illustrated in the drawing these hooks may be formed as parts of metallic clips 21 extending longitudinally of and parallel with the side edges of the seat section and provided at their rear ends with eyes 22 in which is mounted the cross rod forming the pivot 18 by which the leg frame 12 is pivotally connected to the rear edge of the seat section.

The links 14 are pivotally connected with the back section at a point intermediate of the lengths of the side edges thereof, slightly closer to one end which for convenience may be termed the lower end when the said back section is in the upright position shown in Figures 1 and 4 for use as a chair element, and are pivotally connected at their front ends with the upper end of the leg frame 13 as by having eyes engaged with the transverse rod 20 thereof, so that the back section is permanently connected with the seat section through the intermediate agency of the support or leg member represented by the pivotally connected leg frames 12 and 13, and is adapted to be folded parallel with the seat section as shown in Figure 3 so as to lie in contact therewith and constitute with the seat and leg or support member a flat conventional portable package.

The bracing members 15 and 16 consist of looped rods pivotally connected as at 21 and 22 with the side edges of the back section at opposite sides of the pivotal connection 23 of the links 14 therewith, the pivotal point 22, however, being closer to the pivotal point 23 than is the pivotal point 21 for a reason

which will be obvious by reference to Figure 2 wherein said supporting members are disposed in position to maintain the back section in parallel relation with the seat section 5 to form a table top, and with the cross bars 15^a and 16^a of said bracing members resting upon the surface of the seat section.

In the position of the parts adapting the device to be used as a table it is obvious that 10 the link 14 will serve as diagonal braces, tending to prevent a movement of the back section longitudinally with relation to the seat section, but in order that the rigidity of the structure in this adjustment may be assured, the links are preferably provided with 15 hooks members 24 for engagement with the upper bracing loops 15, when the device is set up as a table, as indicated in Figure 2, the length of the nose or finger 24^a of each 20 hook 24 being such that when the parts are brought to the position indicated in Figure 2 with the links 14 inclined to form braces and the loops 15 and 16 disposed in substantially vertical planes, the extremity of said 25 nose or finger will be below the plane of the upper surface of the seat section so that disengagement of the loop 15 from the hooks 24 is prevented. The sides of the loop member 15 are preferably offset outwardly as 30 shown at 15^b to provide for facility in the engagement thereof with said hooks 24.

Having described the invention, what is claimed as new and useful is:—

1. A convertible table and chair having 35 seat and back sections of which the latter is longer than the former, pivotally connected intersecting leg frames of which one is pivoted to the seat section and the other is adapted for detachable engagement therewith, links connecting intermediate points 40 of the side edges of the back section with the upper end of the second-named leg frame, and swinging brace loops carried by the back section for arrangement in bearing 45 contact with the seat section to support the back section in parallelism with the seat section.

2. A convertible table and chair having 50 seat and back sections of which the latter is longer than the former, pivotally connected intersecting leg frames of which one is pivoted to the seat section and the other is adapted for detachable engagement therewith, links connecting intermediate points 55 of the side edges of the back section with the upper end of the second-named leg frame, and swinging brace loops carried by the back section for arrangement in bearing 60 contact with the seat section to support the back section in parallelism with the seat section, the seat section being provided at its front edge with returned hooks for engagement with the cross rod at the upper

end of the said second-named leg frame to constitute the said detachable connection 65 therewith.

3. A convertible table and chair having seat and back sections of which the latter is longer than the former, pivotally connected intersecting leg frames of which one 70 is pivoted to the seat section and the other is adapted for detachable engagement therewith, links connecting intermediate points of the side edges of the back section with the upper end of the second-named leg frame, and swinging brace loops carried by the back section for arrangement in bearing 75 contact with the seat section to support the back section in parallelism with the seat section, the sides of the leg frames being 80 transversely spaced at a distance exceeding the width of the seat section to permit of the folding of the leg frames and seat section to occupy a common plane.

4. A convertible table and chair having 85 seat and back sections of which the latter is longer than the former, pivotally connected intersecting leg frames of which one is pivoted to the seat section and the other is adapted for detachable engagement therewith, links connecting intermediate points 90 of the side edges of the back section with the upper end of the second-named leg frame, and swinging brace loops carried by the back section for arrangement in bearing 95 contact with the seat section to support the back section in parallelism with the seat section, the said links being provided with hooks for engagement with the free end of the brace loop which bears upon the seat 100 section adjacent to the upper end of the second named leg frame.

5. A convertible table and chair having seat and back sections of which the latter is longer than the former, pivotally connected intersecting leg frames of which one is pivoted to the seat section and the other is adapted for detachable engagement therewith, links connecting intermediate points 105 of the side edges of the back section with the upper end of the second-named leg frame, and swinging brace loops carried by the back section for arrangement in bearing 110 contact with the seat section in support of the back section in parallelism with the seat section, the said links being provided with hooks for engagement with the free end of the brace loop which bears upon the seat section adjacent to the upper end of the second named leg frame, and said hooks having their throats closed by the seat section 115 when the back section is parallel with the seat section.

In testimony whereof he affixes his signature.

TILLMAN B. WORTHINGTON.
